U.S. Appl. No. 29/718,062, filed Dec. 20, 2019, Nalen et al.
Sacks, P.C.(57) CLAIMThe ornamental design for a beverage machine, as shown and described.

DESCRIPTION

FIG. 1 is a top, front, and left side perspective view of a beverage machine according to our new design;
FIG. 2 is a left side elevation view thereof;
FIG. 3 is a right side elevation view thereof;
FIG. 4 is a front elevation view thereof;
FIG. 5 is a rear elevation view thereof;
FIG. 6 is a top plan view thereof;
FIG. 7 is a bottom plan view thereof; and,
FIG. 8 is a top, front, and right side perspective view thereof.
The dot-dash broken lines represent boundaries of the claimed design and form no part of the claimed design. The dash-dot broken lines depict portions of the beverage machine that form no part of the claimed design.

1 Claim, 6 Drawing Sheets(56)
